UNITED STATES PATENT OFFICE.

HORACE WYMAN, OF WORCESTER, MASSACHUSETTS, ASSIGNOR TO THE CROMPTON & KNOWLES LOOM WORKS, OF SAME PLACE.

WARP STOP-MOTION FOR LOOMS.

SPECIFICATION forming part of Letters Patent No. 665,591, dated January 8, 1901.

Application filed March 24, 1900. Serial No. 9,990. (No model.)

To all whom it may concern:

Be it known that I, HORACE WYMAN, of Worcester, county of Worcester, State of Massachusetts, have invented an Improvement in

5 Warp Stop-Motions for Looms, of which the following description, in connection with the accompanying drawings, is a specification, like characters on the drawings representing like parts.

10 The invention to be hereinafter described relates to warp stop mechanisms employed in looms to effect the stopping thereof whenever a warp-thread breaks or becomes too slack, and more particularly to such type of mechanism wherein on the occurrence of such fault in the warp an electric circuit is established or completed, which, through coacting instrumentalities, brings the loom to a stop.

For the present embodiment of my invention I have selected the general form of warp stop mechanism described and set forth in United States Letters Patent No. 631,243, wherein when a warp-thread breaks or becomes too slack a drop device or warp-detector falls into the path of a moving feeler and arrests the free movement thereof, thereby causing certain other instrumentalities to act to disengage the shipper from its holding-notch and stop the loom.

20 In my present invention I have entirely dispensed with the instrumentalities referred to and have devised electrically-actuated devices which upon the indication of a defect in the warp-threads by dropping of a drop device or warp-detector into the path of movement of the feeler will cause an electric circuit to be established or completed, to thereby put into position a device to be struck by a moving part of the loom, and thereby be actuated to effect the stopping of the latter.

To effect a saving of the batteries or other source of electrical supply, it is desirable in such forms of warp stop mechanisms to break the circuit and cut out the electric current

45 as soon as the stopping mechanism has acted; and to this end I have provided devices which will act to automatically accomplish this desired end simultaneously with the stopping of the loom.

50 Other objects and advantages of the inven-

tion will hereinafter appear, and the novel features thereof be fully described in the following specification, and be definitely pointed out in the claims.

In the drawings, Figure 1 represents a right-hand side elevation of a sufficient portion of a loom to enable the invention to be understood. Fig. 1^a is a detail showing the form of drop device or warp-detector employed. Fig. 1^b is a detail of the binding-posts in section through which the circuit is formed. Fig. 2 is a detail, partly in section, of one end of the loom-frame, showing the shipper and its coacting parts. Figs. 3 and 3^a are side and end elevations, respectively, of the automatic switch or cut-out for interrupting the circuit through the loom when the latter is stopped. Figs. 4 and 5 are enlarged details in side and rear elevations, respectively, showing the means for operating the feeler and the electric contacts. Fig. 6 is a cross-section taken through the guide-bars and the feeler and showing the drop devices in their normal position suspended by warp-threads.

In the drawings the loom-frame A, the lay A', carrying the reed a; the lay being pivoted at A⁶, the crank-shaft A⁴, having the usual cranks receiving lay-actuating connecting-rods A⁵, the cam-shaft A⁷, driven from the gear A⁹ on the crank-shaft engaging a gear A⁸ on the cam-shaft, said gears being represented in circular outline only, the shipper-handle E, working in the slot of extension a', notched at one side and connected with the loom-frame at one end of the usual breast-beam A², the shed-forming devices a² and a³, the removable end piece C, having suitable guide-bars c³ and c⁴, said end pieces and their connected guide-bars being supported in a suitable casting B, extended across the loom-frame, and the rock-shaft e⁶, sustained in suitable bearings e⁹ and carrying a vibrator or feeler e⁷, are or may be substantially as represented in said Patent No. 631,243.

Herein the casting B is sustained by 95 screws 2, inserted in cross-bars 3, said screws and other screws 4 being also extended through bearings 5, sustaining each a proper lease-rod 6, said rods also sustaining the warps near the points where the drop devices 100

7 are suspended. The drop devices are composed of thin metal provided each, as herein represented, with a single long slot 8 to embrace a guide-bar c^3 or c^4 , each of said drop devices at its lower end being provided with a notch 9, a slit 10 being made from the bottom of said notch into the lower end of the slot 8, said slit being provided to enable a drop device to be readily applied to a guide-bar or to be removed from a guide-bar, as desired. The slit also enables a new drop device to be put onto a warp-thread in position in case of an accident or breakage of one of said devices.

- 15 The side frame of the loom, preferably at the end adjacent the shipper-handle E, has applied to it, by means of a proper screw or securing-bolt 15, Fig. 2, a stand 16, having an ear 17, against which normally rests a toe 20 18 of a dagger-carrier 19, mounted to turn about a pivot or stud 20 in said stand, the lower end of the carrier having jointed to it at 21 (see dotted lines, Fig. 1) a dagger 22, a spring 23, interposed between the lower end 25 of said carrier and the under side of the ear 17, acting normally to maintain the pivot 21 in the position represented in Fig. 1 of the drawings. Preferably below the dagger-carrier 19 and supported by the stand 16 is an 30 electromagnet b, whose armature b', pivoted to the stand 16, is normally held out of contact with the magnet b by means of a spring b². Said armature carries a dagger-supporting arm b³, which when the loom is in normal 35 operating condition supports said dagger with its end b⁴ above the path of movement of the bunter 28, adjustably secured to the bracket 31, carried by the lay, by means of the slot 30 and pins or screws 29.
- 40 The electromagnet b is, by means of the wires b⁵ b⁶ b⁹, in electric circuit with the binding-posts b⁷ b⁸, which when a warp-thread breaks are, by mechanism to be hereinafter described, put into electric connection to 45 thereby complete the circuit and establish a current derived from a battery P or any usual source of electrical energy and energize the magnet b. Under such condition it will be evident that the armature will be drawn toward the magnet in opposition to the spring b², and its dagger-supporting arm b³ will be moved to permit the dagger 22 to fall into the path of the bunter 28 and be moved thereby 50 to turn the dagger-carrier on its pivot 20 and through the knock-off lever 34 to disengage 55 the shipper from its holding-notch in the extension α' , and thus stop the loom.

It will be evident that should a drop device fall and the circuit be completed, as above 60 described, the current would continue to flow indefinitely or until the drop device were raised from its position to complete the circuit if some means were not devised to interrupt the circuit as the loom is stopped, and 65 to this end I have interposed a switch or cut-out in the circuit between the electromagnet b or battery and the binding-posts b⁷ b⁸, which

as the shipper moves to stop the loom will be automatically operated to interrupt the circuit, as will now be described.

70 Mounted on or secured to the loom-frame adjacent the shipper-handle E is a bracket d, which supports two ordinary insulated binding-posts d³ and d⁴, to which are electrically connected the wires b⁶ and b⁹ and which together constitute one of the circuit-wires or conductors between the battery P or other source of electrical energy and one of the binding-posts b⁷ or b⁸. The posts d³ and d⁴ are in electrical connection, respectively, through 75 the arms d⁵ d⁶, with the spring contact-plates d' d², which are electrically separated from each other by the insulation d⁷ and from the supporting-bracket d by the insulation d⁸. Pivotedly connected to the bracket d by the 80 pin d⁹ is a switch-arm d¹⁰, having an upturned or cam-end d¹¹ and carrying a switch or contact-plate d¹², bent upon itself, and the parts of which are properly insulated from each other by the insulation d¹³ and also from the 85 switch-arm d¹⁰, to which it is secured by the screw d¹⁴, as shown. The switch or contact-plate d¹² is properly shaped to enter between the contact-plates d' d² to form electrical connection between them and is normally held 90 between said plates by the spring d¹⁵, as shown. Secured to the shipper-handle E, in position to engage the upturned or cam end of the arm d¹⁰ as the shipper is moved to stop the loom, is a shoe d¹⁶, which, as it rides over said upturned or cam end of the arm d¹⁰, forces said arm against the action of the spring d¹⁵ and withdraws the switch or contact-plate d¹² from 95 between the contact-plates d' d², and, as in the extreme position of such movement of the 100 shipper, the shoe d¹⁶ still engages the upturned or cam end of the arm d¹⁰, the said plate d¹² will be maintained out of contact with the plates d' d² to effectually interrupt the 105 circuit and prevent the passage of the electric 110 current during the time the loom is not running.

In order to insure the proper positioning of the dagger to meet the bunter 28, it is desirable that means be employed to prevent a 115 return of the dagger-supporting arm b³ to its raised position after it has been depressed by the completion of the circuit and said circuit has been interrupted by the movement of the shipper, and to this end there is secured to 120 the loom side, as herein represented, a stand 24, having a projection 25, which constitutes the fulcrum of a retaining-catch 26, having cooperating with it a spring 27, which acts 125 normally to put the upper end of the latch into the path of movement of the dagger-supporting arm b³. At its upper end the latch has a hook 32, which when the dagger-supporting arm b³ is caused to drop by the movement of the armature, due to the energization 130 of the electromagnet b, will catch over the top of said arm and retain the same in its lowered position. A pin 35, secured to the stand 24, limits the movement of the latch under the

impulse of the spring 27, so that it remains in proper position to engage the dagger-supporting arm b^3 . The lower arm 36 of the latch projects into the path of movement of a lug or cam 12, carried by a yoke 14, secured to the shipper-handle E in a manner such that the stopping movement of the shipper will raise the arm 36, release the dagger-supporting arm b^3 from the catch, and permit the 10 same to rise and carry the dagger again into inoperative position. Thus on completion of the circuit by the drop devices and contacts (to be described) the magnet b is energized, the dagger and its supporting-arm b^3 are 15 lowered, and the latter is held in such lowered position by catch 26 to enable the dagger to be engaged by the bunter, at which time the shipper is disengaged from its holding-notch and moves to stop the loom. Such movement 20 of the shipper at once interrupts the current and breaks the circuit through the switch, as above described, thus releasing the armature to its spring b^2 , and the same movement of the shipper releases the catch 26 from the 25 dagger-supporting arm, as described, and the parts are thus automatically reset.

Preferably in the rear of the loom-frame I provide the drop devices or warp-detectors, which, in connection with a continuously-actuated feeler, complete the circuit when a warp-thread breaks or becomes slack, as will best be understood from Figs. 4 and 5.

Sustained by and pivoted on the stud 43 is the actuator or arm 45, which at its lower end carries a pin 40, on which the initiatory device 39 is pivoted, and provided at its lower end with a slot 42, which is engaged by the pin e^4 on an arm of the feeler rock-shaft e^6 . Secured to the actuator 45 is an arm 46, carrying the lugs or brackets 49 through a suitable perforation, in which a pin 48 is adapted to slide endwise. At its end adjacent the actuator and initiatory device the pin carries a shoe 47, which, bearing upon the latter under the stress of a spring 44, maintains said initiatory device during the normal operation of the loom in line with the actuator, but which, upon an obstruction to the free movement of the lower end of the initiatory device, will permit the latter to turn upon its pivot-stud 40. The upper end of the initiatory device is carried into the axial line of the stud 43, where it is provided with suitable insulation f' .

Mounted upon the cam-shaft A⁷, Fig. 1, is a cam 62, having a cam-groove 61, in which travels a pin or roller 60, carried by an arm 57, pivoted to the bracket 59 on the stud 58. At its opposite end the arm 57 is provided with a slot 56, which is engaged by a pin 55, secured to the lower end of a connecting-rod 52, the upper end of which is jointed to the arm 46 through the stud and sleeve 51, a suitable set-screw 53 being provided to adjustably secure the rod 52 to said sleeve 51. From 65 the construction thus described it will be obvious that motion of the arm 57, imparted to the arm 46 from the cam 62, will vibrate the

actuator 45, and through the initiatory device will move the feeler e^7 back and forth below the warp drop devices when they are in their 70 normal raised position, and the upper end of the initiatory device carrying the insulation f' being in the axial line of the stud 43 will have no movement relative to said stud. Should a warp-thread break or become slack, 75 however, the drop device carried thereby will fall into the path of and obstruct the movement of the feeler e^7 , whereupon as the actuator 45 continues to move under the actuating influence of the cam 62, rod 52, and arm 80 46 the flexing connection between the actuator and initiatory device will cause the upper end of the said device to be moved to one side or the other of the axial line of the stud 43 and complete an electric circuit by means 85 now to be described.

Supported on a bracket f^2 , secured to the loom-frame by a screw or bolt f^3 and insulated therefrom by the insulating material f^4 , are the electric contact-plates or positive and 90 negative electrodes $f^5 f^5$ and $f^6 f^6$, of which contact-plates $f^5 f^5$ are provided at their lower ends with suitable guide-openings, wherein is supported and free to slide to a limited extent a contact slide-bar f^{10} . The 95 contact-plates or electrodes $f^5 f^5$ are preferably, though not necessarily, formed as a single piece of conducting material and are supported, preferably, from the under side of the insulating material f^4 by the binding-posts 100 $b^7 b^8$, from one of which, as b^7 , they are insulated by the insulating-bushing f^7 , but with the other of which, as b^8 , they are in electrical connection, as will be apparent from Fig. 1^b.

The contact-plates $f^6 f^6$ are preferably supported from the upper surface of the insulating material f^4 and are also secured thereto by the binding-posts $b^7 b^8$, from one of which, as b^8 , they are insulated by the insulating-bushing f^8 , but with the other of which, as 110 b^7 , they are in electrical connection.

The contact slide-bar f^{10} carries two studs or pins $n n$, which embrace between them the upper insulated end f' of the initiatory device, and on the side of said bar opposite the 115 pins $n n$ the said bar carries a pin f , which projects therefrom between the converging ends of the contact-plates $f^6 f^6$.

From the construction as above described it will be obvious that so long as the warp-threads remain in normal condition the upper end f' of the initiatory device being in the axial center of stud 43 will have no relative movement therewith; but should a warp-thread break or become too slack the drop 125 device will fall and arrest the movement of the feeler, whereupon the upper end f' of the initiatory device will be moved relative to the stud 43 to the right or left, according to the direction of movement at the time of the actuator 45. Such movement of the initiatory device will cause the upper insulated end f' to contact with one or the other of the pins or studs $n n$ and move the contact slide-bar 130

f^{10} to bring the pin f carried thereby into electrical contact with one or the other of the depending ends of the contacts f^6 f^6 and, through said pin f , slide-bar f^{10} , contacts f^5 f^6 , 5 posts b^7 b^8 , and electromagnet b to thereby stop the loom, as hereinbefore explained, and by the movement of the shipper to cut out the battery from the loom.

While I have disclosed the above particular

- 10 construction of contact-plates, slide-bar, posts, and coöperating parts as the preferred embodiment of my invention, it is to be understood that my invention is not limited thereto, as these parts may be varied through a large 15 range of construction and still be within the scope of my invention, which, among other things, as pointed out, contemplates the stopping of the loom on the arrest of the movable feeler by means of an electric circuit thereby 20 established.

I have used in the foregoing specification the term "contact-plates," they constituting electrodes.

Having thus described my invention, what 25 I claim, and desire to secure by Letters Patent, is—

1. In a warp stop-motion for looms, a series 30 of drop devices maintained in normal position by warp-threads, a movable feeler, means including an electric circuit to stop the loom and devices movable on the arrest of the feeler to complete the circuit.

2. In a warp stop-motion for looms, a series 35 of drop devices maintained in normal position by warp-threads, a movable feeler, an electric circuit including an electromagnet, devices movable on arrest of the feeler to complete the circuit, and means under control of said magnet to stop the loom.

3. In a warp stop-motion for looms, a series 40 of drop devices maintained in normal position by warp-threads, a movable feeler adapted to be arrested by a drop device in its abnormal position, an electric circuit, and means movable on the arrest of the feeler to complete said circuit and stopping mechanism under control of said circuit to stop the loom.

4. In a warp stop-motion for looms, a series 45 of drop devices maintained in normal position by warp-threads, a movable feeler adapted to be arrested by a drop device in abnormal position, an electric circuit, means under control of said circuit to stop the loom, and an initiatory device made movable on the arrest 50 of the feeler to close said circuit.

5. In a warp stop-motion for looms, a series 55 of drop devices maintained in normal position by warp-threads, a feeler, and means to move it, said feeler adapted to be arrested by a drop device in abnormal position, an electric circuit, means under control of said circuit to stop the loom, an initiatory device and means insulated from said device and made operative thereby on the arrest of the feeler 60 to complete the circuit.

6. In a loom the following instrumentalities, viz: a series of drop devices maintained

in normal position by warp-threads, a feeler and means to move it to feel for an abnormally-positioned drop device, an electric circuit, means under control of said circuit to stop the loom, an initiatory device, and a contact-slide insulated from but movable by said device on the arrest of the feeler to complete the circuit.

75

7. In a loom the following instrumentalities, viz: a shipper-handle, a dagger, a supporting-arm acting to normally hold said dagger in inoperative position, an electric circuit including an electromagnet, warp drop devices, a feeler, and means made operative on the arrest of the feeler to close the circuit and thereby permit the dagger to assume operative position and stop the loom.

8. In a warp stop-motion for looms, a shipper-handle, a dagger to release said shipper-handle, a supporting-arm to hold said dagger in inoperative position, a series of drop devices maintained in normal position by warp-threads, a feeler movable in opposite directions, an electric circuit including an electromagnet, contact-plates, and a device set in motion by arrest of the feeler by a drop device in abnormal position, said device coöperating with one or the other of said contact-95 plates according to the direction of movement of the feeler at the time its movement is arrested.

9. In a loom the following instrumentalities, viz: a shipper, means including an electric circuit to free the shipper from its holding-notch when a warp-thread breaks or becomes slack, a switch interposed in said electric circuit, means normally tending to hold the switch closed, and devices carried by the shipper to open the switch on movement of the shipper and acting on one member of the switch to stop the loom.

10. In a loom the following instrumentalities, viz: a shipper, means including an electric circuit to free the shipper from its holding-notch when a warp-thread breaks or becomes too slack, a switch in said circuit comprising a fixed member and a movable member, a spring for normally closing said switch, means on the shipper independent of the switch acting on the said movable member to open the switch against the tension of the spring as the shipper moves to stop the loom.

11. In a loom the following instrumentalities, viz: a shipper, a dagger, a supporting-arm for said dagger, an electric circuit including an electromagnet for moving the said arm from its supporting position and permitting the dagger to move into position to be struck by a moving part of the loom when a warp-thread breaks or becomes too slack, and a catch for holding the supporting-arm out of supporting position.

12. In a loom the following instrumentalities, viz: a shipper, a dagger, a supporting-arm for said dagger, an electric circuit including an electromagnet for moving the said arm from its supporting position and permit-

ting the dagger to move into position to be struck by a moving part of the loom when a warp-thread breaks or becomes too slack, and a catch for holding the supporting-arm out of supporting position, and means on the shipper to trip the catch and release the supporting-arm therefrom, as the shipper moves to stop the loom.

13. In a loom, a shipper, a dagger, means to hold it in an inoperative position, an electric circuit, including an electromagnet to place said dagger into an operative position to be struck by a moving part of the loom when the electric circuit is completed by the breaking of a warp-thread, and means to retain said dagger in operative position after the circuit is broken.

14. In a loom, a shipper, a dagger, means to hold it in an inoperative position, an electric circuit, including an electromagnet to place said dagger into an operative position to be struck by a moving part of the loom when the electric circuit is completed by the breaking of a warp-thread, and means to retain said dagger in operative position after the circuit is broken, and means to restore said dagger to its inoperative position when the shipper is moved.

15. In a warp stop-motion, a series of drop devices normally suspended on warp-threads, means to detect a drop device in its abnormal position by the breaking of a warp-thread, combined with two contact-plate terminals, or electrodes of an electric circuit, and means

outside of the drop devices to complete the 35 circuit between the electrodes upon the breaking of the warp-thread.

16. In a warp stop-motion for looms, a series of drop devices normally suspended on warp-threads, means to detect a drop device 40 in its abnormal position due to the breaking of a warp-thread, combined with two pairs of electrodes of negative and positive poles, and means coöperating, first with one and next with the other pair of electrodes, alternately, to, upon the breaking of a warp-thread, establish an electric current in the circuit through that pair of electrodes with which its coöperating means is acting at the time of the detection of the drop device in its abnormal 50 position.

17. In an electrical detecting device, consisting of an open electric circuit, a detector mechanism to close the circuit, two pairs of electrodes of the negative and positive poles, 55 means coöperating first with one and then with the other pair of electrodes, alternately, to establish an electric current through the circuit through that pair of electrodes through which its coöperating means is acting at the 60 time the detector indicates to close the circuit.

In testimony whereof I have signed my name to this specification in the presence of two subscribing witnesses.

HORACE WYMAN.
